CLAIM

The ornamental design for a "specimen imaging tray," as shown and described.

DESCRIPTION

FIG. 1 is a top perspective view of a specimen imaging tray, showing our new design.

FIG. 2 is a bottom perspective view of the specimen imaging tray of FIG. 1.

FIG. 3 is a front view of the specimen imaging tray of FIG. 1.

FIG. 4 is a rear view of the specimen imaging tray of FIG. 1.

FIG. 5 is a left side view of the specimen imaging tray of FIG. 1.

FIG. 6 is a top view of the specimen imaging tray of FIG. 1; and,

FIG. 7 is a bottom view of the specimen imaging tray of FIG. 1.

A right side view of the specimen imaging tray of FIG. 1 is not presented because it is a mirror image of the left side view of FIG. 5.
